(57) **CLAIM**

The ornamental design for an aggressive eater curved dog bowl, as shown and described.

DESCRIPTION

FIG. 1 is a front perspective view of our new design for an aggressive eater curved dog bowl;

FIG. 2 is a bottom perspective view of our new invention;

FIG. 3 is a top plan view of our new invention;

FIG. 4 is a bottom plan view of our new invention;

FIG. 5 is a front elevation view of our new invention;

FIG. 6 is a rear elevation view of our new invention;

FIG. 7 is a right side elevation view of our new invention; and,

FIG. 8 is a left side elevation view of our new invention.

Any portions of the interior of the bowl which are not visible in the drawings form no part of the claimed design.

1 Claim, 5 Drawing Sheets
